JOHN W. GRAHAM, OF CHILLICOTHE, OHIO.

Letters Patent No. 90,356, dated May 25, 1869.

IMPROVEMENT IN LAMP-POSTS.

The Schedule referred to in these Letters Patent and making part of the same.

To all whom it may concern:

Be it known that I, JOHN W. GRAHAM, of Chillicothe, Ross county, State of Ohio, have invented a new and improved Mode of Constructing Lamp-Posts; and I do hereby declare that the following is a full, clear, and exact description of the construction and operation of the same, reference being had to the annexed drawings, making a part of this specification, in which—

Figure 1 is a perspective view, with the lamp attached, and showing the base *a* and service-pipe and main.

Figure 2 is a vertical sectional view, showing the closed bottom *a* and the opening *b*, into which the service-pipe *c* is screwed, or otherwise secured.

Figure 4 is a sectional view of the lower section, or base, with closed bottom, to be attached to either old or new posts.

Figure 3 is a view of plug, which is to be leaded into the top of the lamp-post, to be provided with a short piece of gas-pipe and stop-cock, to which the burner is to be attached, as shown in fig. 1.

The nature of the invention consists in casting the lamp-post with a closed bottom, *a*, and having an opening, *b*, at a proper height, into which is secured the service-pipe *c*, while the top of the post is provided with the plug, short pipe, and stop-cock, as shown in fig. 1 and fig. 3.

The advantages claimed by this mode of construction are—

First, economy, by dispensing with the ten or more feet of gas-pipe usually employed inside the post.

Second, the large gas-space inside the lamp-post prevents the gas freezing up and obstructing the delivery in the coldest weather.

Third, the dust, dirt, and condensation of moisture, or impurities fall to the bottom *a*, without obstructing the entrance of gas at *b*, and its passage to the burner, and exit at the burner.

Fourth, the lamp-posts made on this plan are more durable, because oxidation can take place only on the exterior.

The lamp-post may be cast with the bottom at *a* closed, or a sleeve or short pipe, fig. 4, or its equivalent, secured to the bottom in any convenient manner.

The ordinary lamp-post may be fitted with a closed bottom in this manner.

Having thus described my invention,

What I claim, and desire to secure by Letters Patent of the United States, is—

1. The plug, fig. 3, provided with a short pipe and stop-cock, in combination with a lamp-post, constructed in the manner herein described, substantially as and for the purposes specified.

2. The enlarged reservoir *d*, with closed bottom *a*, to attach to the foot of iron lamp-posts, constructed as and for the purposes herein set forth.

Witnesses:

JOHN W. GRAHAM.
